ARTICLE OF JEWELRY AND CLASP
THEREFORIrwin Pratt, Brooklyn, and Wolf Bernard
Wollman, Jackson Heights, N. Y.

Application April 23, 1946, Serial No. 664,196

8 Claims. (Cl. 63—2)

1

This invention relates to an article of jewelry in the nature of a bracelet or necklace; more particularly, our invention relates to an article of jewelry in the nature of a bracelet or necklace and clasp therefor.

It is contemplated by our invention, and it is an object thereof, to provide in combination with or for use with an ornamental strand, braid, rope or like flexible element, a clasp which may join one terminal end of such element with the body portion of the element so that a side by side overlap connection may be effected. It is contemplated by our invention to provide in an article of jewelry comprising a braid, rope, string, chain, snake-chain, wire, or narrow band, a clasp whereby the ornamental strand element, which may or may not be extensible, may be convoluted by the wearer so as to provide either a bracelet or necklace.

Still more particularly, it is an object of our invention to provide a clasp whereby elongated jewelry strand elements, such as a mesh band, a string of pearls, wire, rope, braid, band, link, chain may be held in predetermined overlapping position against relative slidable movement in order to permit a wide variety of arrangement of the extensible strand element, in the form of convolutes, knots or other ornamental configurations.

Still further objects of our invention reside in the provision of a clasp for holding relatively indeterminate lengths of material in adjusted position.

To obtain these objects and such further objects as may appear herein or be hereinafter pointed out, we make reference to the accompanying drawing, forming a part hereof, in which—

Figure 1 is a perspective view showing our invention in the form of a necklace;

Figure 2 is a perspective view showing the same device as a bracelet;

Figure 3 is a section taken on the line 3—3 of Figure 1;

Figure 4 is a section taken on the line 4—4 of Figure 2;

Figure 5 is a perspective view showing the clasp element;

Figure 6 is a section taken on the line 6—6 of Figure 5;

Figure 7 is a fragmentary perspective view showing another method of arranging the item illustrated in Figures 1 and 2.

Making reference to the drawing, it is contemplated by us to provide for a strand element of indeterminate length, such as a snake chain, braid, rope, band, chain, string of pearls, string

2

of beads, means for joining this relatively flexible element in variously convoluted positions. In the illustration, the flexible strand of indeterminate length comprises a snake chain 10 (i.e. 5 closely coiled wire generally tubularly formed and partially laminated) whose terminal ends 11 and 12 may be convoluted to form an overlap, contacting at 13.

The terminal ends 11 and 12 are each anchored 10 in a clasp 14 comprising a body portion 15, one end of which is formed with a loop 16. The branch 17 has hinged to it a locking element 18 by the complementary intermeshing knuckles 19, through which the pintle-pin 20 passes. The 15 bow shaped locking element has a latching nose 21, engaging the lip 22, formed on the upper curved end of the body portion 15. An ear 23 provides finger engaging extension for manual 20 operation, to move the locking element from latched position against the engagement of the nose and lip.

It will be observed that the clasp 14 as thus described defines a permanent loop in the form of a socket 24 and a detachable locking loop 25. 25 The socket 24 may be closed by a side wall 26, though this wall may be omitted for purposes which will appear hereinafter.

From the construction shown, one terminal of the strand 12 is anchored in the socket 24 as by 30 soldering, brazing or the like. The terminal 11 has the complementary clasp turned with the locking loop upwardly directed.

When in overlapping position, as shown in Figure 1 and by releasing the locking loop manually, the strand may be moved through the loops 35 25 to secure any desired adjustment of the strand parts in relation to each other to accommodate the neck of the wearer, or to encircle the same in any desirable way.

40 This same piece of jewelry may be convoluted upon the wrist of the wearer to provide a bracelet such as shown in Figure 2, in which event the strand is long enough to have several contiguous convolutions 27, 28, 29, 30 and 31.

45 It will be observed that the terminal portion 11 carrying the clasp 14 may engage the adjacent convolution 28 and that the terminal 12, carrying another reversely positioned clasp 14, may engage the contiguous convolution 30.

50 While we have shown the clasp with a side wall 26 closing the loop 24 where this desirably forms a socket for a terminal end of the strand, it will be understood that this side wall element may be omitted, in which event the loop left 55 thereby may slidably be mounted along the

length of the strand to any desired position, leaving the locking loop free for engagement along the contiguous section of the strand.

It will also be understood that the locking element 18 is designed to provide a frictional fit over the strand which is directed between the jaws formed by the body element 15 and the locking element 18, when the nose 21 and lip 22 are latched.

It will be understood that the body element 15 may have attached to it, on its outwardly faced side any desirable form of ornamentation. In the illustration, floral settings 32 and 33 are shown affixed to the clasps at the terminal ends 11 and 12, respectively, to fortify the aesthetic appearance of the clasps at these points.

It will further be understood that while we have described and illustrated the strand convoluted contiguously in overlapping position in Figures 1 and 2, in the former figure to form a necklace and in the latter figure to form a bracelet, the strand may be directed into ornamental twisted designs, as more clearly illustrated in Figure 7.

It will be understood that while we have shown a pair of clasps at the terminal ends of the strands, a single clasp may be used to act as a "shortener" for any strand of indeterminate length providing an easily adjustable connection. Thus, the permanent loop portion of the clasp may have passed therethrough one element of the strand and the locking jaw may thereafter be used to pinch and hold the strand in a predeterminedly adjusted position, upon manually snapping or latching the hingeable locking element into engagement over the strand.

It will be understood that while we have illustrated a so-called snake type of flexible strand other strands may be employed, such as the heretofore mentioned string of pearls or beads, a mesh braid or metal ribbon, a drawn metal rope or a chain.

It will be understood that while we have described and illustrated our invention in connection with an extensible type of article of jewelry, which may be readily converted from a necklace to a bracelet or vice versa, wherein the convolutions are contiguous, it will be understood that the overlapping ends of the strands may be intertwined to present different ornamental effects.

It will also be understood that while we have described and illustrated a strand wherein the convolutions are contiguous, the strand may be draped upon the body of the wearer in various other forms, which will readily be apparent to the skilled jeweler.

It will also be observed that the clasp which we provide, including the strap-like member which defines a pair of spaced-apart loops to frictionally hold the strand member which is correspondingly shaped, serves to hold the layers of strands contiguously, to give an immobile effect.

Our invention though illustrated in the form of a continuous strand for alteration from a necklace to a bracelet, is applicable to strands of like nature employed as part of a wrist-watch bracelet such as an expanding flexible or non-flexible bracelet holding a watch. Especially is this valuable to the extensible spring type bracelet which, in time, may become distended. By our invention the distension caused by fatigue of the springs or elongation of the link members may be compensated by sliding the clasp member

to a new position to take up the slack due to wear.

Having thus described our invention and illustrated its use, what we claim as new and desire to secure by Letters Patent, is:

1. In an extensible type of bracelet, necklace or like article of jewelry comprising a strand member, arranged to be convoluted to be accommodated to different sizes, the combination therewith of a clasp comprising adjacent loop portions arranged in parallelism, one of which loop portions is closed and the other of which is formed from the body and has a branch directed over the same with an end extended substantially radially thereof, pivot means on said end hingedly mounting a disengageable locking element, cooperating with the body of the clasp to form the second loop, the locking element in the detached position forming an open sided loop for lateral attachment of the clasp to any portion of the strand member.

2. In an extensible type of bracelet, necklace or the like article of jewelry comprising a strand member of indeterminate length arranged to be convoluted to be accommodated to different sizes, a terminal of which strand has attached thereto a clasp comprising adjacent loops, one of which loops is closed and the other of which is formed from the body and includes a branch thereof directed over the same with an end extended substantially radially thereof, pivot means on said end provided with a hingeable locking element forming a detachable closure for the other loop and engaging the body portion thereof, the locking element in the detached position forming an open sided loop for lateral attachment of the clasp to any portion of the strand member.

3. In an extensible type of bracelet, necklace or the like article of jewelry comprising a strand member of indeterminate length arranged to be convoluted to be accommodated to different sizes, a terminal of which strand has attached thereto a clasp comprising adjacent loops, one of which loops is closed and the other of which is formed from the body and includes a branch thereof directed over the same with an end extended substantially radially thereof, pivot means on said end provided with a hingeable locking element forming a detachable closure for the second loop and engaging the body portion thereof, said locking element and body portion of said clasp having inter-engaging latching connections, the locking element in the detached position forming an open sided loop for lateral attachment of the clasp to any portion of the strand member.

4. In an article of jewelry of the character described comprising a strand, adjacent each end whereof there is provided a clasp to hold portions of said strand contiguously and including a body portion having a branch defining a complete loop, and an extension portion the said branch of which loop extends over the extension and includes hinged thereto a locking element cooperating with the extension portion to provide a second loop, to hold portions of said strand contiguously, the locking element in the detached position forming an open sided loop for lateral attachment of the clasp to any portion of the strand member.

5. In an article of jewelry of the character described comprising a strand, adjacent each end whereof there is provided a clasp to hold portions of said strand contiguously and including a body portion having a branch defining a complete loop, and an extension portion, the said branch of which loop extends over the extension

and includes hinged thereto a locking element cooperating with the extension portion to provide a second loop, to hold portions of said strand contiguously, said first loop including a side wall defining a socket to receive a terminal portion of said strand, the locking element in the detached position forming an open sided loop for lateral attachment of the clasp to any portion of the strand member.

6. An article of jewelry comprising a clasp of a rigid, strap-like member, shaped to form a substantially U-shaped bend terminating into a short branch portion and a long branch portion, the short branch portion having pivoted to the free end thereof, a hingeable locking element cooperating with the long branch portion to form an encircling loop whereby strand members may be held in contiguous position, and means for latching the locking element and long branch portion to each other, the locking element in the detached position forming an open sided loop for lateral attachment of the clasp to any portion of the strand member.

7. An article of jewelry comprising a clasp of a rigid, strap-like member, shaped to form a substantially U-shaped bend terminating into a short branch portion, and a long branch portion, the

short branch portion having pivoted to the free end thereof a hingeable locking element cooperating with the long branch portion to form an encircling loop whereby strand members may be held in contiguous position, and means for latching the locking element and long branch portion to each other, comprising a complementarily spaced latching nose and engaging lip, the locking element in the detached position forming an open sided loop for lateral attachment of the clasp to any portion of the strand member.

8. An article of jewelry in accordance with claim 6 wherein said U-shaped bend is formed at one side thereof with a wall forming a socket in which a terminal end of the strand may be anchored.
